UNITED STATES PATENT OFFICE.

JAMES ALEXANDRE BELLON-LENCAUCHEZ, (CALLED J. A. LENCAUCHEZ,) OF PARIS, FRANCE.

PROCESS OF PURIFYING GAS.

SPECIFICATION forming part of Letters Patent No. 727,266, dated May 5, 1903.

Application filed August 6, 1901. Serial No. 71,058. (No specimens.)

To all whom it may concern:

Be it known that I, JAMES ALEXANDRE BELLON-LENCAUCHEZ, (called J. A. LENCAUCHEZ,) a citizen of the Republic of France, and a resident of Paris, France, have invented a new and useful Improvement in the Purification of High-Furnace and Like Gases, which is fully set forth in the following specification.

10 This invention relates to an improved process of purifying gases such as those obtained from gas-generating furnaces, high furnaces, &c., which, as is well known, often carry a large amount of suspended matter which cannot be 15 eliminated satisfactorily even in the most perfectly-constructed scrubbers or other existing washing apparatus.

The dust carried and suspended in the gases of high furnaces and referred to by 20 manufacturers as "sublimed" is composed of silica, lime, alumina, magnesia, oxid of iron, carbonates of lime and magnesia, and other substances in the form of impalpable powdered substances of a greasy nature, which 25 are capable of traversing the various channels, galleries, and flues of the gas-generator without becoming deposited and which finally escape through the chimney, notwithstanding the height thereof of fifty meters to 30 seventy meters, and spread over distances of more than eight or ten kilometers area. These objectionable dusts have hitherto resisted every means of purification.

The improved process of purification according to this invention enables, say, high-furnace gases to be treated and purified in a perfect manner; but other gases obtained from various other forms of generators, such as gas-generator furnaces, &c., may equally 40 be treated.

In carrying out my process instead of employing towers or other washers or scrubbers, which occupy large spaces, I prefer to arrange at any convenient point in the conduits for the gas a centrifugal fan or turbine-wheel, into which is directed by any convenient means and at any pressure a cold or hot water current or currents. The centrifugal force of the said fan or turbine produces an 45 intimate contact between and commingling of the gas and the water introduced therein,

and thereby enables the water to completely free the gas of its suspended impurities. This is the characteristic principle of my invention, and, as will be understood, in practice the construction of the fan may be varied to suit different requirements; but I have found the form of apparatus hereinafter described to give good general results.

Referring to the accompanying drawings, 60 Figure 1 is a longitudinal section of the purifier. Fig. 2 is a vertical cross-section. Fig. 3 is a plan. Fig. 4 is a detail.

The apparatus comprises two oppositely arranged wheels *j j'*, mounted on the inner 65 ends of shafts *k k'*, respectively, which shafts are adapted to be rotated in opposite directions by any suitable mechanism. (Not shown.) Two series of flat blades 1 and 3 are secured to wheel *j* near its periphery and 70 project into close proximity with the adjacent face of wheel *j'*, as clearly shown in Fig. 2, and similar series of blades 2 and 4 are in like manner secured to wheel *j'* and project into close proximity to wheel *j*, the disposition of the series of blades being such that on the rotation of the wheels blades 2 travel in a space between blades 1 and 3, while blades 3 travel in a space between blades 2 and 4, all as clearly shown in Figs. 1 and 2. 80 A is a gas-supply conduit bifurcated at its delivery end to form passages *a a'*, the former terminating at the side of wheel *j* and the latter at the side of wheel *j'*. Shaft *k* at its inner end is journaled in a bearing *e*, supported 85 upon the bottom of passage *a*, Fig. 4, and at its outer end passes through stuffing-box *c* in side plate *b* of passage *a* and is journaled in a standard *d*. Shaft *k'* is supported in similar bearings. This arrangement permits the 90 outer bearings to be mounted in position after the assembling of the inner parts of the apparatus and enables the same to be mounted in a perfectly level position.

ff, Figs. 2 and 3, are water-delivery nozzles 95 which project through the walls of passages *a a'* and project water from opposite sides in the form of a spray between the spokes of wheels *j j'* and into the space between the lower parts of said wheels, where it is at once 100 subjected to the action of the moving blades.

The inner bearings *e* may be lubricated by

means of externally-located oil-pots *g*, Fig. 2, each provided with a supply-tube *h*, leading to the bearing.

In the operation of the apparatus the gas 5 delivered from passages *a a'* and the water delivered from nozzles *ff* into the space between the centrifugal wheels *j j'* is first acted upon by the series of blades 1, which project the mixture by centrifugal force against the 10 second series of blades 2, moving rapidly in a direction opposite to that of blades 1, thus subjecting the mixture to violent and repeated shocks, which are repeated as the mixture is passed by centrifugal action from blades 2 15 to 3 and in turn from blades 3 to 4. The blades 4 expel the mixture into the exit-conduit B. By reason of the violent shocks to which the gas and water are subjected the latter is atomized and intimately mixed with 20 the gas, both being moved in the same direction by centrifugal force, and the suspended dust or other matter in the gas is thoroughly subjected to the action of the water and after 25 having been moistened thereby settles in the form of greasy slime.

What I claim, and desire to secure by Letters Patent of the United States, is—

1. The herein-described process of purifying gas consisting in intimately commingling 30 the gas with a washing liquid by simultane-

ously agitating the gas and liquid together by centrifugal force causing the gas and liquid introduced at or near the center of rotation to move in the same direction from the center toward the circumference with relation to the axis of rotation and the liquid to be atomized and intimately mixed with the gas. 35

2. The herein-described process of purifying gas consisting in projecting a washing liquid 40 in the form of a spray into contact with the gas, then atomizing the washing liquid and intimately commingling the gas with the liquid by simultaneously agitating the gas and liquid together by centrifugal force causing 45 the gas and liquid introduced at or near the center of rotation to move in the same direction from the center toward the circumference with relation to the axis of rotation at the same time subjecting the mixture of gas 50 and liquid to repeated impacts or shocks.

In testimony whereof I have signed this specification in the presence of two subscribing witnesses.

JAMES ALEXANDRE BELON-LENCAUCHEZ,
(CALLED J. A. LENCAUCHEZ.)
